UNITED STATES PATENT OFFICE.

CALVIN R. DAVIS, OF SOUTH BEND, INDIANA, ASSIGNOR TO OLIVER CHILLED PLOW WORKS, OF SOUTH BEND, INDIANA.

LISTER PLOW AND PLANTER.

SPECIFICATION forming part of Letters Patent No. 757,999, dated April 19, 1904.

Original application filed April 9, 1903, Serial No. 151,831. Divided and this application filed January 20, 1904. Serial No. 189,863. (No model.)

To all whom it may concern:

Be it known that I, CALVIN R. DAVIS, a resident of South Bend, in the county of St. Joseph and State of Indiana, have invented certain new and useful Improvements in Lister Plows and Planters; and I do hereby declare the following to be a full, clear, and exact description of the invention, such as will enable others skilled in the art to which it appertains to make and use the same.

My invention relates to an improvement in lister plows and planters, and more particularly to improved covering-wheels and mounting therefor, this application being a division 15 of application for patent filed by me April 9, 1903, and designated by Serial No. 151,831.

The object of the present invention is to provide improved means for adjusting the angle of inclination of the covering-wheels; and it 20 consists in certain novel features of construction and combinations and arrangements of parts, as will be more fully hereinafter described, and pointed out in the claims.

In the accompanying drawings, Figure 1 is 25 a view in end elevation, illustrating my improvements; and Fig. 2 is a view of the axle-bearing bracket removed.

1 represents the frame of a sulky-lister converging at its rear end, where a tubular bracket 2 is securely bolted and supported on a standard 3. To the lower end of said standard an adjustable wheel-axle-bearing bracket 4 is secured by a bolt 5, passed through a sleeve 6^a on the bracket and through standard 3 there- 30 in. The bracket 4 is provided with notched or toothed elongated openings or slots 6 to receive bolts 7, passed through ears 8 on the lower side of sand-bands 9, in which axle-stubs 10 are secured, and on said stubs the covering-wheels 11 are mounted. Ears 12 are pro- 35 vided on the upper side of sand-bands 9 and perforated for the reception of bolts 13, passed through holes 14 in bracket 4 and pivot- 40 ally support the axle-stubs, permitting their angle of inclination to be varied by adjusting 45 bolts 7 in the notched or toothed openings or

slots 6, and thereby adjust the angle of inclination of the covering-wheels 11.

Slight changes might be made in the general form and arrangement of the parts described without departing from my invention, and hence I do not restrict myself to the precise details set forth, but consider myself at liberty to make such slight changes and alterations as fairly fall within the spirit and scope 50 of my invention.

Having fully described my invention, what I claim as new, and desire to secure by Letters Patent, is—

1. In a sulky-lister, the combination with a 60 bracket secured to the frame thereof, of sand-bands having ears at both sides, bolts pivotally securing the upper ears, bolts passing through the lower ears and through elongated slots in the bracket, said elongated slots having 65 notched walls, to clamp the sand-bands at any angle, stubs secured in said sand-bands, and covering-wheels on said stubs.

2. In a sulky-lister, the combination with a 70 standard, and a frame supported at its rear end by said standard, of a bracket secured to the lower end of said standard and having openings therein and elongated slots curved concentrically with said openings and having notched walls, sand-bands, stubs in said sand-bands, covering-wheels on the stubs, perforated ears on opposite sides of the sand-bands, bolts passed through one ear of each of said sand-bands and through the openings in the bracket to pivotally support the stubs, and other bolts passed through the other ears on the sand-bands and through the elongated slots in the bracket to secure the stubs and covering-wheels at the desired angle of inclination. 75 80

In testimony whereof I have signed this 85 specification in the presence of two subscribing witnesses.

CALVIN R. DAVIS.
